CLAIM

The ornamental design for a handle for a kitchen appliance door, as shown and described.

DESCRIPTION

1. Handle for a kitchen appliance door
- 1.1 : Top left perspective view
- 1.2 : Top right perspective view
- 1.3 : Bottom right perspective view
- 1.4 : Front
- 1.5 : Right side view
- 1.6 : Left side view
- 1.7 : Bottom

The broken lines shown on the handle illustrates portions of the handle that form no part of the claimed design; the dashed lines around the handle are for environmental purposes only and form no part of the claimed design.
